UNITED STATES PATENT OFFICE.

JAMES KEITH AND GEORGE KEITH, OF LONDON, ENGLAND.

LIGHTING DEVICE FOR INCANDESCENT GAS-BURNERS.

SPECIFICATION forming part of Letters Patent No. 728,242, dated May 19, 1903.

Application filed August 19, 1902. Serial No. 120,257. (No model.)

To all whom it may concern:

Be it known that we, JAMES KEITH and GEORGE KEITH, subjects of the King of the United Kingdom of Great Britain and Ireland, residing at 27 Farringdon avenue, London, England, have invented certain new and useful Improvements in Lighting Devices for Incandescent Gas-Burners, (for which application for patent has been made in Great Britain, No. 11,644, dated May 22, 1902,) of which the following is a specification.

This invention relates to devices for lighting incandescent gas-burners by means of an electric spark through the intervention of a by-pass pilot-light; and it has for its object to so construct and arrange the tap by-pass and relative devices that the by-pass is automatically cut off on the burner being lighted, so that a saving of gas is effected, and risk of fire due to the pilot-light being left burning is avoided.

In the accompanying drawings, which illustrate the invention, Figure 1 is an elevation, Fig. 2 is a sectional elevation, and Fig. 3 a plan, of the device when the burner is "full on." Figs. 4 and 5 are elevation and sectional elevation, respectively, of the device when the burner and by-pass are both "on," and Figs. 6 and 7 are elevation and sectional elevation when burner and by-pass are both "off."

As shown in the drawings, the burner-base is furnished with a plug-tap *b*, operated by a cross-lever *c*, to which a chain or other hand-pull *d* may be attached, the tap *b* having an orifice *e*, which assumes one of three positions—first, that in which it is transversely of the throughway-passagé *f*, so that the gas-supply is cut-off; second, when it is in line with the throughway *f*, so that the gas is full on, and, third, when turned beyond the full-on position, so that it is open both to the throughway *f* and to a by-pass orifice *h*, leading to a pilot-lighting tube *j*, one or both ends of the orifice *e* in the plug *b* being enlarged for this purpose. The pilot-lighting tube *j* is formed with a number of jet-orifices *k*, up which the flame travels or climbs when the gas issuing from the lowest jet or orifice *h* is ignited by an electric spark, the igniting-spark being produced between a spring-wire *m* on an insulated terminal *l* of an electric-

battery circuit secured on or alongside the by-pass tube and a like wire *n* on an arm *o* of the chain-lever *c*, which operates the tap *b*. 55 These springs are brought into rubbing contact and pass each other, so as to produce an electric spark on the making and breaking of the circuit.

In the operation of the device when the burner is to be lighted the chain *d* is pulled, so as to turn the tap *b* from the off position to and beyond the full-on position, whereby the by-pass and burner are both opened to the gas-supply and the spring-wires make 65 and break contact, so that an electric spark is produced which ignites the lowest of the gas-jets of the climbing by-pass, the jets *k* being lighted one from the other until the uppermost jet impinges on the incandescent mantle. The usual stops limit the extent of motion of this tap. Around the end of the tap *b* is coiled a spring *q*, the free end of which is brought to bear on a stop-pin *r*, so placed that when the pull on the chain *d* is relieved 75 the spring *q* turns back the tap *b* to the full-on position, in which it cuts off the by-pass after the burner has been lighted instead of the by-pass jet or jets being allowed to burn. The size of the by-pass jets *k* may be regulated by a screw *s* entering the by-pass tube *j*, and the jet-orifices may be carried spirally around the tube, so that the ignition-jet for the burner may be at right angles to that ignited by the electric spark. 85

For applying the electric current one pole of the battery may be attached to the gas-main at any convenient point and an insulated wire run with a branch to each light, or for lighting street-lamps the battery may be 90 carried by the lamplighter and the contact made through the lighting-pole.

Having now described the invention, what we claim, and desire to secure by Letters Patent, is—

In a lighting device for incandescent gas-burners, the combination with a burner-supply pipe of a by-pass, a tap having orifices adapted to open the supply-pipe to the burner and on further turning to the by-pass also, a 100 cross-lever operating said tap, a pull at either end of said lever, a spring acting on said lever to turn the tap to full-on position, a wire spring at one end of said lever, a pilot-light-

ing tube connected with the by-pass and having a helical row of jet-orifices, means for regulating the admission of gas to the tube, a wire spring in electrical circuit fixed near 5 the pilot-tube and adapted to make and break contact with the spring at the end of the lever and by means of a spark to ignite a jet in the lowest orifice of the pilot-tube when the tap is turned against spring-pressure to be

open to the by-pass as well as the burner, 10 substantially as described.

In witness whereof we have hereunto set our hands in presence of two witnesses.

JAMES KEITH.
GEORGE KEITH.
